UNITED STATES PATENT OFFICE

2,586,525

WINDOW FRAME AND SASH ASSEMBLY

Harold Edwards and George H. Goodemote, Syracuse, N. Y., assignors to The O. M. Edwards Company, Inc., Syracuse, N. Y., a corporation of New York

Application August 8, 1947, Serial No. 767,444

1 Claim. (Cl. 189—69)

1

This invention relates to window constructions for vehicles, as busses, railway cars, and the like, and has for its object a compact assembly of the window frame and sash in the frame to have a limited swinging opening movement for ventilating purposes without hinged joints, or other joints, which would result in rattling.

It is particularly adapted for window frame and sash assemblies used in air conditioned vehicles where the sash is opened, as a wind wing for ventilating purposes only at rare intervals, as when the air conditioning system fails.

More specifically, the invention has for its object an assembly of a window frame and swinging sash in which the mounting permitting the swinging of the sash consists merely of a resilient flexible leaf, preferably flat, which requires but a thin space and hence requires no extra thickness of the frame, or the sash, and which contains no joints to become loose and rattle.

The invention consists in the features and constructions hereinafter set forth and claimed.

In describing this invention, reference is had to the accompanying drawings in which like characters designate corresponding parts in all the views.

Figure 1 is a face view of a window embodying this invention.

Figure 2 is an enlarged sectional view on line 2—2, Figure 1, the contiguous portion of the car body structure around the window opening being also shown.

Figure 3 is a detail isometric view of one of the spring leaves between the window frame and the sash.

In the drawing, 1 and 2 designate the window frame and the sash respectively, the frame 1 being mounted in the window opening 3 formed in the body structure 4 of the vehicle. The body structure is here shown as formed with an angular inwardly extending circumferential flange 5 around the window opening and parallel to the plane of the sash, this serving as an abutment for the window frame inserted into the window opening from the opposite or outer side of the body structure. This flange 5 is covered by a circumferential sealing strip 6 of flexible compressible material, as rubber, or rubber composition. The window frame is secured in the window opening as by screws 7. A sealing strip 8 is also interposed between the outer edge of the window frame and the wall of the window opening 3. The window frame 1 and the sash 2 are usually formed of extruded metal.

The sash 2 includes double or spaced glass

5 panels 9 and the mounting 10 therefor of rubber, or rubber composition, the mounting being located in a channel in the sash and one side of this channel is formed by a demountable retaining plate 11 removable for removing and replacing the glass panels 9 and their mounting 10. This plate is secured to the body of the sash, as by screws 12. The sash 2 nests in the window frame 1, and the frame 1 is formed with an angular flange 13 extending inward in a plane parallel to the plane of the sash in position to provide an abutment against which the sash seats when the sash is closed. A sealing strip 14 is interposed between the edge of the sash and the opposing edge of the frame 1.

10 The means for connecting the sash 2 to the frame 1 to permit a limited swinging opening movement of the sash includes one or more spring leaves 15. The spring leaf is usually flat and of stainless steel, and one edge thereof extends into a recess or slot 16 in an upright member of the window frame and open at one end toward the edge of the opposing frame member of the sash, and the other end of the spring extends into a complementary recess or slot 17 opening through the edge of the opposing sash frame member and preferably aligned with the recess or slot 16, the outer side wall of the recess or slot 17 being provided by a portion of the retaining plate 11. The opposite ends of the leaf are secured to the frame 1 and to the sash 2 as by screws 18 and 19 respectively, the screws 18 extending through holes in the frame and into threaded openings 20 in a reinforcing strip 21 on the leaf 15. The reinforcing strip 21 serves as a nut. The leaves 25 extend across a clearance or space 14A between the confronting faces of the adjacent upright frame members of the window frame and sash, which clearance permits flexing of the leaves. The frame 1 is formed with unthreaded bores 22 30 for receiving the ends of the screws 18.

35 The opposite edge of the leaf is formed with countersinks or perforated bosses 23 for receiving the heads of the screws 19, the latter threading into the sash 2. One side of the slot or recess 17 in the sash 2 diverges towards the edge of the sash to permit the flexing movement of the leaf during the opening of the sash 2 and likewise, the opposite or edge of the sash toward the exterior of the car body diverges as at 24 40 from a complementary diverging face 25 on the frame 1 to permit the opening limited movement of the sash. The sealing strip 14 is provided with a flange portion 26 extending between the diverging surfaces 24, 25.

45 The leaves 15 are here shown as mounted on

an upright member of the frame 1, preferably the upright member toward the front of the vehicle, with respect to the direction of travel, so that the rear end of the sash swings as a winging outward, as indicated in broken lines, Figure 2.

The sash is held closed by a latching device 27, this being so constructed that it is difficult to operate by curious persons or tamperers. The construction of the latch forms no part of this invention.

In operation, when the latch is unlatched and an outward force applied to the sash of the interior of the bus body, the sash will swing outward a limited amount and the leaves flex an amount determined by the divergence of the surfaces 24, 25, and of the wall of the slot or recess 17. Owing to the relative arrangement of the hinge leaves, no extra space in a widthwise direction is required, and owing to the hinge leaf there are no hinge joints to loosen and the entire structure is particularly compact and also the sash is nested weather tightly in the window frame.

What we claim is:

In a window frame and sash assembly, a window frame; a sash nested in the frame and a spring leaf extending edgewise relative to the sash at one side face of the sash and anchored at its opposite ends to the frame and to the sash, the frame and the sash being spaced apart along

the edge faces thereof on which the spring leaf is located, providing a clearance recess through which the spring leaf extends to permit the spring leaf to flex about an axis located in the recess, the window frame being formed with an angular inwardly extending abutment flange extending circumferentially around one side face of the sash against which the sash abuts when closed, the abutment flange closing the recess along one side face of the sash when the sash is closed, the recess being formed to provide an angular portion on the side of the sash and frame opposite to that on which the abutment flange is located so that the edge of the sash laps the opposing portion of the frame.

HAROLD EDWARDS.

GEORGE H. GOODEMOTÉ.
